Primary Examiner — Marianne Pandozzi(74) *Attorney, Agent, or Firm* — Renner, Otto, Boiselle & Sklar, LLP(57) **CLAIM**

The ornamental design for a bowl, as shown and described.

DESCRIPTION

FIG. 1 is a top, front, right perspective view of a bowl showing our new design;

FIG. 2 is a front elevation view thereof, a rear elevation view, right side elevation view and left side elevation view being a mirror image of the front elevation view;

FIG. 3 is a top plan view thereof; and,

FIG. 4 is a bottom plan view thereof.

The broken lines in the drawing depict portions of the bowl that form no part of the claimed design.
